WILLIAM J. BARR, OF CLEVELAND, OHIO.

CIRCUIT-CONTROLLING MECHANISM FOR ELECTRICALLY-HEATED TOOLS.

No. 852,537.

Specification of Letters Patent.

Patented May 7, 1907.

Application filed April 19, 1906. Serial No. 312,685.

To all whom it may concern:

Be it known that I, WILLIAM J. BARR, a citizen of the United States of America, residing at Cleveland, in the county of Cuyahoga and State of Ohio, have invented certain new and useful Improvements in Circuit-Controlling Mechanism for Electrically-Heated Tools or Instruments, &c.; and I hereby declare the following to be a full, clear, and exact description of the invention, such as will enable others skilled in the art to which it pertains to make and use the same.

This invention relates to improvements in circuit-controlling mechanisms or devices more especially designed for electrically heated tools or instruments, such, for instance, as sad-irons, and pertains more especially to circuit-controlling mechanism adapted to be removably attached or borne by the handle of a sad-iron and comprising a suitably supported lever which is actuated against the action of a suitably applied spring during the grasping of the grip of the handle, with the arrangement of the members of the circuit-closing mechanism such that the electric circuit of which the electroheating resistance of the sad-iron forms a part is normally open but closed by the actuation of the lever against the action of the spring during the grasping of the grip of the handle preparatory to the use of the sad-iron.

The primary object of this invention is to provide circuit-controlling mechanism of the character indicated which is exceedingly simple and durable in construction, that can be conveniently operated and that is reliable in its operation.

With this object in view, and to the end of realizing other advantages hereinafter appearing, this invention consists in certain features of construction, and combinations of parts, hereinafter described and pointed out in the claims.

In the accompanying drawings, wherein like letters, numerals or reference-characters are employed to indicate like parts, Figure 1 is a side elevation of a portion of a sad-iron whose handle is provided with my improved circuit-controlling mechanism, and in this figure the body of the sad-iron and the casing of the circuit-controlling mechanism are in section to more clearly show the construction. Fig. 2 is a right hand side elevation relative to Fig. 1. In this figure the electric source is diagrammatically illustrated, and the sheet metal wall of the casing of the cir-

cuit-controlling mechanism is removed. Fig. 3 is a vertical section on line 3—3, Fig. 1, looking inwardly. Fig. 4 is a vertical section on line 4—4, Fig. 1, looking outwardly. Fig. 5 is a vertical section on line 5—5, Fig. 1, looking outwardly. Fig. 6 is a horizontal section on line 6—6, Fig. 1, looking downwardly. Fig. 7 is a horizontal section on line 7—7, Fig. 3, looking downwardly. Figs. 8 and 9 are views largely corresponding with Figs. 1 and 2, except that Figs. 8 and 9 illustrate the actuation of the circuit-closer of my improved circuit-controlling mechanism into an operative position, and Fig. 9 illustrates the operation of the means employed in locking the circuit-closer in an operative position.

The drawings are made on an enlarged scale and portions are broken away in the drawings to reduce their size and to more clearly show certain features of construction.

Referring to the drawings, A indicates the body of the sad-iron. The body A is provided interiorly with an electroheating resistance C which is constructed or formed in any approved manner and employed in heating the bottom or ironing surface of the body of the sad-iron.

B indicates the handle of the sad-iron, and v, the handle-top or grip of the handle. The handle B is secured to the body A in any approved manner.

The handle B is provided at one end of the handle with a vertically arranged flat surface 10 against which abuts the casing E of my improved circuit-controlling mechanism which casing (see Figs. 1 and 2) is provided interiorly with a chamber 12 in which my improved circuit-controlling mechanism is largely contained, which chamber has a top wall 13, a bottom 14, two laterally spaced upright side walls 15 and 15 and an upright wall 16 arranged between the walls 15 and 15 and abutting against the surface 10 of the handle. The chamber 12 is also provided with an upright wall 17 which is spaced a suitable distance outwardly from and opposite the wall 16. The wall 17 extends between the top wall 13 and bottom 14 and is removably secured to the bottom and top wall by screws 18. The wall 17 is composed preferably of a sheet-metal piece. The top wall 13, the bottom 14 and the upright walls 15, 15 and 16 of the chamber 12 are composed preferably of a single casting which is preferably removably secured to the handle B by suitably applied screws D which prefer-

ably extend into the handle from within the wall 16 and have their heads countersunk within the said wall, as shown in dotted lines, Fig. 1. The top wall 13 is provided centrally between the side walls 15 and 15 and a suitable distance outwardly from the wall 16 with a hole 20 which extends vertically through the said top wall.

A lever F (see Figs. 1 and 2) is pivoted horizontally and transversely of the sad-iron between the hole 20 and the upper end of the wall 17 to the top wall 13 by a pin f which is arranged horizontally and at a right angle to the grip b and extends through the top wall 13 and through two ears 19 integral with the lever F and preferably formed upon and depending from the lever at opposite ends respectively of the said pin. The lever F extends from its point of attachment to the upper end of the casing E to and over and longitudinally of the grip b of the handle B and is normally spaced a suitable distance from the said grip. The lever is obviously capable of being swung in a vertical plane toward and from the grip b. The lever F is provided with a hole 22 arranged over the hole 20 in the top of the casing E. The hole 22 accommodates the extension through the lever of two insulated wires H and h which electrically connect with opposite terminals respectively of a generator or electric source G which is diagrammatically illustrated in Fig. 2. The hole 20 in the top wall 13 accommodates the extension of the wires H and h downwardly through the said wall into the chamber 12, and the said wires within the upper end of the said chamber are electrically connected in any approved manner with stationary contacts K and k respectively removably secured to the said wall 13 by screws 24 which are insulated from the casing E, as at 25, as shown very clearly in Fig. 4. The contacts K and k are spaced laterally within the upper portion of the chamber 12 of the casing E. The contacts K and k are arranged a suitable distance from the wall 16 of the chamber 12 and the lower portions of the said contacts possess springiness and preferably incline somewhat downwardly and outwardly from the sad-iron-handle. Two vertically movable contact-fingers L and l have their upper portions overlapping the lower inclined portion of the stationary contacts K and k respectively. The said upper portions of the contact-fingers L and l possess springiness and preferably somewhat inclined upwardly and inwardly. The lower portions of the contact-fingers L and l (see Figs. 1 and 2) are arranged vertically over stationary contacts M and m respectively which are mounted upon the bottom 14 of the chamber 12 and electrically connected in any approved manner by suitably applied binding posts P and p respectively with wires N and n which are electrically connected with opposite terminals

respectively of the electroheating resistance C of the sad-iron. The binding-posts P and p and contacts M and m are insulated from the casing E, as at 26, as shown very clearly in Fig. 5. The contacts M and m are each provided with two oppositely arranged spring jaws 28 which are relatively arranged to form a V-shaped space between them as shown in Fig. 1. The arrangement of the parts is such that the contact-fingers L and l are normally 75 in their upper positions out of contact with the contacts K k and M m.

The arrangement of the parts is such that during the downward movement of the fingers L and l the contact-finger L will 80 establish electrical connection between the contacts K and M and the contact-finger l will establish electrical connection between the contacts k and m, and that the contact-fingers L and l will pass between and spread 85 apart the jaws 28 of the contacts M and m respectively. The contact-fingers L and l obviously constitute the circuit-closing means or circuit-closer of my improved circuit-controlling mechanism. The contact-fingers L and l are of course operated simultaneously and are preferably removably secured by means of screws 30 to a block R of insulating material, such, for instance, as hard vulcanized fiber. The block R is movable vertically within the chamber 12 below the contacts K and k, and the arrangement of the parts is such that in the upper and normal position of the block R the contact-fingers L and l or circuit-closing means are 90 out of electrical connection with the contacts K and k and M and m and consequently in an inoperative position which is the normal position of the circuit-closing means or circuit-closer. The block R is provided with a 95 screw-threaded hole r which extends vertically through the block, and a vertically arranged sleeve S is screw-threaded externally at its lower end and screwed into the block R at the hole r. The block R and sleeve S 100 are therefore rigid with each other. The sleeve S in its upper and normal position,—that is, in the inoperative position of the circuit-closing means,—abuts against the top wall 13 of the chamber 12, which wall limits 105 upward movement of the said sleeve and connected block and circuit-closing means. 110

A tubular casing T rests upon the bottom 14 of the chamber 12 and extends upwardly into the sleeve S, and a spiral spring u surrounds the casing T and is confined between the said bottom 14 and the lower ends of the block R and sleeve S. The spring u acts to retain the block R and connected sleeve S and circuit-closing means in their upper and 115 normal position.

A plunger W extends loosely through a hole 32 which is formed in and extends vertically through the top wall 13 of the chamber 12 vertically above the upper end of the 120

casing T. (See Figs. 1 and 3). The plunger W has lateral bearing within the said wall 13 and extends from the under side of the lever S downwardly through the hole 32 into the sleeve S and into the upper end of the casing T, and a spiral spring z is confined within the casing T below the lower end of the plunger W and acts to retain the plunger and connected lever F in their upper and normal position. The plunger W in its upper and normal position abuts against the under side of the lever E, as shown in Fig. 1, and the plunger is provided below the top wall 13 of the chamber 12 with a pin w which extends horizontally and laterally through the plunger beyond opposite sides of the plunger, and in the normal position of the plunger abuts against the wall 13, as shown very clearly in Fig. 3, and limits upward movement of the plunger. The pin w projects laterally of opposite sides of the plunger W through opposite sides respectively of the upper end of the sleeve S which is provided in its upper edge (see Figs. 3 and 7) with recesses 33 engaged by the ends of the pin w. The pin w establishes operative connection between the plunger W and the sleeve S for the purpose of lowering the said sleeve and connected block and circuit-closing means during the downward actuation of the plunger. It will be observed that the pin w not only co-operates with the top wall 13 in limiting upward movement of the plunger, but constitutes means instrumental in transmitting motion to the sleeve from the plunger during the downward movement of the plunger. The wall 16 is enlarged in thickness, as at 34, around the adjacent portion of the sleeve S, as shown very clearly in Fig. 7, and the thicker portion 34 of the said wall not only forms a lateral bearing therefore to the said sleeve but extends into close proximity to the ends of the pin w and therefore co-operates with the said pin in preventing turning of the plunger and sleeve.

Means for locking the circuit-closing means in an operative position is provided and comprises preferably a latch y which is arranged in an upright position within the chamber 12 adjacent the thicker portion 34 of the wall 16 and is pivoted at its lower end and horizontally, as at 35, (see Fig. 3) to the said wall. The latch y is arranged within its axis at a right angle to the axis of the lever F. The latch y is arranged to render it capable of being swung toward and from the sleeve S, and the upper end portion of the said latch curves upwardly and toward the said sleeve and in the upper and normal position of the plunger abuts at its upper end against the adjacent end face of the pin w, as shown in Fig. 3. A suitably applied spring 36 is confined between the rear side of the latch and the adjacent wall 15 and acts to swing the latch toward the sleeve S. The

latch y is provided at its forward side with two teeth 37 and 38 having downwardly and forwardly sloping upper sides and spaced vertically and forming a notch 39 between them (see Fig. 3) and the sleeve S is provided a suitable distance below its upper end with a tooth 40 which projects somewhat upwardly and laterally toward the latch y. In the normal position of the parts the tooth 40 is above the notched portion of the latch y, and the arrangement of the parts is such that during the downward actuation of the plunger to render the circuit-closing means operative the pin w disengages the upper end of the latch y to permit the forward movement of the latch by the spring 36 and the sleeve-tooth 40 comes into engagement first with the notch 39 and then moves adown the inclined top surface of the lower tooth 38 and becomes overhung by the last-mentioned tooth.

The sheet-metal wall 17 of the casing E is preferably extended, as at 42, downwardly below the bottom 14 and in under the binding-posts P and p, as shown in Figs. 1 and 5.

The operation of my improved circuit-controlling mechanism is as follows:—The operator in grasping the grip b of the handle B also grasps the lever F and swings the lever downwardly and toward the said grip and obviously retains the said lever in its downwardly swung position while he works with the iron. That end of the grip b which is adjacent the casing E limits the downward movement of the lever. During the downward movement of the lever the plunger W is depressed or lowered against the action of the spring z. During the downward actuation of the plunger the sleeve S and connected block R and circuit-closing means are actuated downwardly against the action of the spring u. During the downward movement of the insulating block R the circuit-closing means formed by the contact-fingers L and l is rendered operative and the electric circuit comprising the generator or electric source G, the wires H and h, the contacts K and k, the contact fingers L and l, the contacts M and m, the binding posts P and p, the wires N and n and the resistance C is closed as required to effect a heating of the ironing surface of the sad-iron. The arrangement of the parts is preferably such that the contact-fingers L and l during their downward movement will engage the contacts K and k respectively before they connect with the contacts M and m respectively. As soon as the tooth of the sleeve S during the actuation of the circuit-closing means into an operative position comes in under the upper tooth 37 of the latch the contact-fingers L and l will simultaneously come into engagement with the contacts M and m respectively so that the contact-fingers L and l as they come into engagement with the contacts M and m respec-

tively will be locked against upward movement by the overlapping of the sleeve-tooth 40 by the upper latch-tooth 37, as shown in Fig. 9, so that the contact-fingers L and l when once rendered operative are retained in an operative position while the grip b and lever F are within the grasp of the operator. Of course, a proper grasp of the grip b and lever F will swing the said lever the full distance and not merely part way, as illustrated in Fig. 8, and the arrangement of the parts is such that when the lever is swung the full distance in the direction of the grip b the sleeve-tooth 40 shall have moved in under the lower latch-tooth 38 and be overhung by the said latch-tooth. When the lever F is released the plunger W is elevated by the action of the spring x, and the lever is swung upwardly by the upward movement of the plunger. The plunger moves upwardly until its pin w strikes against the top wall 13 of the chamber 12. During the upward actuation of the plunger the pin w actuates the latch y against the action of the spring 36 and disengages the said latch from the sleeve-tooth so as to permit the said sleeve and the connected circuit-closing means to be actuated into their normal position by the spring u, and the pin w upon the actuation of the plunger into its normal position engages and retains the latch in its normal and inoperative position as shown in Fig. 3.

My improved circuit-controlling mechanism, being wholly carried by a casing removably secured to an end of the sad-iron, is out of the way of the grip of the handle and has all of its component members and wire connections readily accessible for repairs.

What I claim is:—

1. The combination, with the body of a sad-iron; a handle attached to the body, and electroheating resistance within the body, of an interiorly chambered casing rigid with the handle, with the interior chamber of the casing having a top wall, a bottom, two opposite walls spaced laterally of the sad-iron, an upright wall arranged between the two laterally spaced walls and overlapping the adjacent portion of the handle, with the said upright walls, bottom and top wall formed of a single casting, said chamber having a sheet metal wall arranged opposite and a suitable distance from the handle-overlapping wall and removably secured to adjacent portions of the casing; suitably supported separated contacts arranged within the aforesaid chamber and adapted to participate in the formation of an electric circuit comprising the aforesaid resistance, and a suitably supported circuit-closer normally arranged in an inoperative position but movable to establish electrical connection between the contacts.

2. The combination, with the body of a sad-iron, and a handle attached to the body, of an interiorly chambered casing arranged

at one end of and rigid with the handle, with the interior chamber of the casing having a top wall, a bottom, two opposite upright walls spaced laterally of the sad-iron, an upright wall arranged between the two laterally spaced walls and overlapping and secured to the aforesaid end of the handle, with the said upright walls, bottom and top wall formed of a single piece, said chamber also having a wall arranged opposite and a suitable distance from the handle-overlapping wall and removably secured to adjacent portions of the casing, and means for establishing an electric circuit which comprises an electroheating resistance within the body of the sad-iron, an electric source, suitably supported separated contacts arranged within the aforesaid chamber, and a suitably supported circuit-closer normally arranged in an inoperative position but movable to establish electrical connection between the contacts.

3. The combination, with the body of a sad-iron; a handle attached to the body, and the electroheating resistance of the sad-iron, of a casing forming a chamber and arranged at one end of and rigid with the handle; separated contacts arranged within the chamber of and supported but insulated from the casing, which contacts are adapted to participate in the formation of an electric circuit comprising the aforesaid resistance; a circuit-closer for establishing electrical connection between the contacts, which circuit-closer is normally arranged in an inoperative position but movable into its circuit-closing or operative position, and means within the aforesaid chamber for locking the circuit-closer upon the actuation of the circuit-closer into its operative position.

4. The combination, with the body of a sad-iron; a handle attached to the body, and the electroheating resistance of the sad-iron, of a casing forming a chamber and extending up and down one end of and rigid with the handle; a circuit-closer contained within the chamber and adapted to close an electric circuit comprising the aforesaid resistance, which circuit-closer is normally in an inoperative position but movable into its circuit-closing and operative position; means whereby the circuit-closer is locked upon the actuation of the circuit-closer into an operative position, and means whereby the said locking means is rendered inoperative during the actuating of the circuit-closer from its operative position into its normal position.

5. The combination, with the body of a sad-iron; a handle attached to the body, and an electroheating resistance within the body, of a circuit-closer arranged externally of the handle and adapted to close an electric circuit comprising the aforesaid resistance, which circuit-closer is normally in an inoperative position but movable into its circuit-

closing and operative position; means whereby the circuit-closer is locked upon the actuation of the circuit-closer into an operative position, and means whereby the said locking means is rendered inoperative during the actuating of the circuit-closer from its operative position into its normal position.

5 6. The combination, with the body of a sad-iron, a handle attached to the body, and the electroheating resistance of the sad-iron, of a casing forming a chamber at one end of the handle; a circuit-closer contained and movable vertically within the said chamber and adapted to close an electric circuit comprising the aforesaid resistance, which circuit-closer is normally in its upper and inoperative position; means acting to retain the circuit-closer in its normal position, and means for actuating the circuit-closer downwardly into an operative position.

10 7. The combination, with the body of a sad-iron; a handle attached to the body, and the electroheating resistance of the sad-iron, of a vertically movable circuit-closer arranged externally of but borne by the handle and adapted to close an electric circuit comprising the aforesaid resistance, which circuit-closer is normally in its upper and inoperative position; means whereby the circuit-closer is locked upon the actuation of the circuit-closer downwardly into an operative position, and means whereby the said locking means is rendered inoperative during the actuating of the circuit-closer from its lower 15 into its upper position.

20 8. The combination, with the body of a sad-iron, a handle attached to the body, and the electroheating resistance of the sad-iron, of a casing forming a chamber at one end of the handle, which casing is rigid with the sad-iron, a circuit-closer arranged and movable within the said chamber and normally in its inoperative position, which circuit-closer is adapted to close an electric circuit comprising the aforesaid resistance, a lever fulcrumed to the said casing, and means whereby motion is transmitted to the circuit-closer from the lever to actuate the circuit-closer into its circuit-closing and operative position.

25 9. The combination, with the body of a sad-iron, a handle having a grip and attached to the body, and the electroheating resistance of the sad-iron, of a casing forming a chamber at one end of the handle, which casing is rigid with the sad-iron, a circuit-closer arranged and movable within the said chamber and normally in its inoperative position, which circuit-closer is adapted to close an electric circuit comprising the aforesaid resistance, a lever fulcrumed to the upper end of the said casing and extending from the casing to and longitudinally of the grip of the handle, and means whereby motion is transmitted to the circuit-closer from

the lever to actuate the circuit-closer into its circuit-closing and operative position during the swinging of the lever toward the grip of the handle in grasping the lever and grip.

30 10. In circuit-controlling mechanism, the combination, with separated contacts adapted to participate in the formation of an electric circuit; circuit-closing means adapted to establish electrical connection between the contacts and normally in an inoperative position but movable into a circuit-closing and operative position, of an insulating block bearing the circuit-closing means and provided with a hole extending through the block; a sleeve extending into the said hole and operatively connected with the block to render it capable of actuating the block in the direction required to render the circuit-closing means operative; a plunger extending into and movable endwise of the sleeve; means acting to retain the plunger in its normal position, and means whereby motion is transmitted from the plunger to the sleeve to actuate the circuit-closing means into an operative position.

35 11. In circuit-controlling mechanism, the combination, with a casing forming a chamber; a suitably supported lever; separated contacts arranged within the chamber and supported but insulated from the casing, which contacts are adapted to participate in the formation of an electric circuit; circuit-closing means adapted to establish electrical connection between the contacts and normally in an inoperative position but movable into a circuit-closing and operative position, of an insulating block bearing the circuit-closing means; a sleeve operatively connected with the block to render it capable of actuating the block in the direction required to render the circuit-closing means operative; a plunger extending into and movable endwise of the sleeve, which plunger is arranged to be actuated by the aforesaid lever in the direction required to actuate the sleeve; means acting to retain the plunger in its normal position; means acting to retain the sleeve and connected circuit-closing means in their normal position, and means for transmitting motion from the plunger to the sleeve to bring the circuit-closing means into an operative position.

40 12. In circuit-controlling mechanism, the combination, of a casing forming a chamber; a lever fulcrumed to the casing; separated suitably supported contacts arranged within the chamber and adapted to participate in the formation of an electric circuit; circuit-closing means adapted to establish electrical connection between the contacts and normally in an inoperative position but movable into a circuit-closing and operative position; a plunger arranged to be actuated by the lever in one direction; means acting to retain the plunger in its normal position, and means

whereby the actuation of the plunger by the aforesaid lever results in the movement of the circuit-closing means into an operative position.

- 5 13. In circuit-controlling mechanism, the combination, with a casing forming a chamber; a lever fulcrumed to the upper end of the casing; suitably supported vertically spaced contacts within the chamber and adapted to 10 participate in the formation of an electric circuit, of circuit-closing means adapted to establish electrical connection between the contacts and normally in an inoperative position but movable into a circuit-closing and 15 operative position; an upright plunger arranged to be actuated by the aforesaid lever in one direction; means acting to retain the plunger in its normal position, and means whereby actuation of the plunger by the lever 20 results in the actuation of the circuit-closing means into an operative position.
14. In circuit-controlling mechanism, the combination, with suitably supported separated contacts adapted to participate in the 25 formation of an electric circuit, and circuit-closing means adapted to establish electrical connection between the contacts and normally in an inoperative position, of an insulating block bearing the circuit-closing means 30 and provided with a screw-threaded hole extending through the block; an externally screw-threaded sleeve screwed into the block; a plunger extending into and movable endwise of the sleeve; means acting to retain the 35 sleeve and connected block and circuit-closing means in their normal position, and means for transmitting motion from the plunger to the sleeve to actuate the circuit-closing means into an operative position.
- 40 15. In circuit-controlling mechanism, the combination, with suitably supported separated contacts adapted to participate in the formation of an electric circuit, and circuit-closing means adapted to establish electrical 45 connection between the contacts and normally in an inoperative position, of an insulating block bearing the circuit-closing means; a sleeve operatively connected with the block to render the circuit-closing means 50 capable of being rendered operative; a plunger extending into and movable endwise of the sleeve and provided with means arranged to actuate the sleeve in the direction required to move the circuit-closing means into a circuit-closing and operative position; means 55 acting to retain the sleeve and connected block and circuit-closing means in their normal position, and means acting to retain the plunger into its normal position.
- 60 16. In circuit-controlling mechanism, the combination, with suitably supported vertically spaced contacts adapted to participate in the formation of an electric circuit, and circuit-closing means adapted to establish 65 electrical connection between the contacts

and normally in an inoperative position, of a suitably supported vertically movable insulating block bearing the circuit-closing means; means acting to retain the block in position holding the circuit-closing means in an inoperative position; an upright plunger; means whereby motion is transmitted to the block by the actuation of the plunger vertically in one direction.

17. In circuit-controlling mechanism, the combination, with a casing forming a chamber; vertically spaced insulated contacts arranged within the chamber and adapted to participate in the formation of an electric circuit, and circuit-closing means arranged 80 within the chamber and adapted to establish electrical connection between the contacts and normally in an inoperative position; means acting to retain the circuit-closing means in its normal position; a plunger extending from above the chamber downwardly into the chamber; means acting to retain the plunger in its upper and normal position, and means whereby the downward actuation of the plunger results in the movement of the circuit-closing means into an operative position.

18. In circuit-controlling mechanism, the combination, with vertically spaced contacts adapted to participate in the formation of an electric circuit; circuit-closing means adapted to establish electrical connection between the contacts and normally in an inoperative position, and an insulating block bearing the circuit-closing means, of a sleeve secured to 95 the block; a plunger extending into and movable endwise of the sleeve and provided with means arranged to actuate the sleeve in the direction required to move the circuit-closing means into a circuit-closing and operative position; a spiral spring acting to retain the plunger in its normal position, and a spiral spring acting to retain the sleeve and connected block and circuit-closing means in 100 their normal position.

19. In circuit-controlling mechanism, the combination, with suitably spaced contacts adapted to participate in the formation of an electric circuit, and circuit-closing means adapted to establish electrical connection between the contacts and normally in an inoperative position, of an insulating block bearing the circuit-closing means and provided with a hole extending vertically through the block; a sleeve extending into the said hole 115 and rigid with the block; a plunger extending into and movable endwise of the sleeve and provided with means arranged to actuate the sleeve endwise in the direction and to the extent required to actuate the circuit-closing means into an operative position; a spiral spring arranged at one end of the plunger and acting to retain the plunger in its normal position; a suitably supported casing 120 extending around the said spring and into 130

the sleeve, and a spring acting to retain the sleeve and connected block and circuit-closing means in their normal position.

20. In circuit-controlling mechanism, the combination, with vertically spaced suitably supported contacts adapted to participate in the formation of an electric circuit; circuit-closing means adapted to establish electrical connection between the contacts and normally in an inoperative position, and an insulating block bearing the circuit-closing means, of an upright plunger arranged to be lowered; a spiral spring suitably confined in under the plunger and acting to retain the plunger in its upper position, and means whereby the downward movement of the plunger results in the actuation of the circuit-closing means into an operative position.

21. In circuit-controlling mechanism, the combination with a casing forming a chamber, with the top wall of the chamber provided with a hole 20; suitably supported vertically spaced contacts arranged in the chamber and adapted to participate in the formation of an electric circuit, and circuit-closing means normally in an inoperative position but movable into a circuit-closing position, of a plunger extending into the chamber from above the chamber; means acting to retain the plunger in its upper and normal position; means whereby the downward actuation of the plunger results in the movement of the circuit-closing means into a circuit-closing position, and a lever arranged above and fulcrumed to the aforesaid casing, which lever extends over the upper end of the plunger and has a hole 22 arranged over the hole in the aforesaid wall of the chamber.

22. In circuit-closing mechanism, the combination, with a casing forming a chamber; suitably supported vertically spaced contacts arranged within the chamber and adapted to participate in the formation of an electric circuit, and circuit-closing means adapted to establish electrical connection between but normally disengaged from the contacts, of a suitably supported vertically movable sleeve arranged within the chamber adjacent one of the upright walls of the chamber; means whereby the downward movement of the sleeve results in actuating the circuit-closing means into a circuit-closing position, and means acting to retain the circuit-closing means in its normal position, and the aforesaid wall of the chamber extending around the adjacent portion of the sleeve so as to afford lateral bearing to the sleeve.

23. In circuit-controlling mechanism, the combination, with vertically spaced suitably supported contacts adapted to participate in the formation of an electric circuit; circuit-closing means adapted to establish electrical connection between the contacts and normally in an inoperative position, of an insulating block bearing the circuit-closing means

and normally arranged to be lowered, of an upright sleeve operatively connected with the block to lower the block, which sleeve is provided in its upper extremity with two recesses arranged at opposite sides respectively of the sleeve; means acting to retain the block and connected sleeve in their upper and normal position; a plunger extending into the sleeve from above and normally arranged to be lowered; means acting to retain the plunger in its upper and normal position, and a pin extending through the plunger and engaging the aforesaid recesses.

24. In circuit-closing mechanism, the combination, with suitably supported separated contacts adapted to participate in the formation of an electric circuit, and circuit-closing means adapted to establish electrical connection between but normally disengaged from the contacts, of a suitably supported vertically movable sleeve operatively connected with the circuit-closing means to actuate the latter into a circuit-closing and operative position, which sleeve is provided in its upper edge with a recess; an endwise movable plunger extending into the sleeve; a pin extending laterally through the plunger and engaging the aforesaid recess, and a stationary member arranged at one side of the pin at both ends of the pin and cooperating with the pin in preventing turning of the sleeve and plunger.

25. In circuit-controlling mechanism, the combination, with vertically spaced suitably supported contacts adapted to participate in the formation of an electric circuit; circuit-closing means adapted to establish electrical connection between the contacts and normally in an inoperative position, and an insulating block bearing the circuit-closing means and normally arranged to be lowered, of an upright sleeve operatively connected with the block to lower the block, which sleeve is provided in its upper extremity with two recesses arranged at opposite sides respectively of the sleeve and has a laterally projecting tooth externally and a suitable distance below the upper end of the sleeve; means acting to retain the sleeve in its upper and normal position; a plunger extending into the sleeve from above and arranged to be lowered; means acting to retain the plunger in its upper and normal position; a pin extending through the plunger and through the aforesaid recesses; a pivotally supported latch having a notch and normally overlapping an end surface of the said pin in the normal position of the plunger and arranged to swing toward the sleeve upon being disengaged by the pin during the downward movement of the plunger, and means acting to swing the said latch toward the sleeve, all arranged and operating substantially as and for the purpose set forth.

26. In circuit-controlling mechanism, the

combination, with vertically spaced suitably supported contacts adapted to participate in the formation of an electric circuit, of circuit-closing means adapted to establish electrical connection between the contacts and normally in an inoperative position; an insulating block bearing the circuit-closing means and normally arranged to be lowered; means for actuating the block downwardly; means acting to retain the block in its upper and normal position, and means for limiting upward movement of the block.

27. In circuit-controlling mechanism, the combination, with vertically spaced contacts adapted to participate in the formation of an electric circuit; circuit-closing means adapted to participate in the formation of an electric circuit; circuit-closing means adapted to establish electrical connection between the contacts and normally in an inoperative position, and an insulating block bearing the circuit-closing means and normally arranged to be lowered, of an upright plunger normally arranged to be lowered; means whereby a downward actuation of the plunger results in the lowering of the block; means acting to retain the plunger in its upper and normal position, and means for limiting upward movement of the plunger.

30. 28. In circuit-controlling mechanism, the combination, with vertically supported contacts adapted to participate in the formation of an electric circuit; circuit-closing means adapted to establish electrical connection between the contacts and normally in an inoperative position, and a block bearing the circuit-closing means and normally arranged to be lowered, of an upright sleeve operatively connected with the block to lower the block and having a laterally projecting tooth externally a suitable distance below the upper end of the sleeve; means acting to retain the sleeve and connected block in their upper and normal position; a pivotally supported latch arranged to swing toward and from the sleeve, which latch has a toothed portion arranged to coöperate with the aforesaid sleeve-tooth in locking the sleeve in the operative position of the circuit-closing means; means acting to swing the said latch toward the sleeve; a plunger extending into the sleeve from above and having a laterally projecting member *w* arranged at the upper end of the sleeve in position to lower the sleeve during the downward movement of the plunger and to actuate the latch and render the latter inoperative during the upward movement of the plunger and retain the latch in an inoperative position in the upper and normal position of the plunger and means acting to retain the plunger in its upper and normal position.

29. In circuit-controlling mechanism, the combination, with separated contacts adapted to participate in the formation of an elec-

tric circuit, and circuit-closing means adapted to establish electrical connection between the contacts and normally in an inoperative position, of an endwise movable sleeve operatively connected with the circuit-closing means to actuate the latter into an operative position, which sleeve is insulated from the circuit-closing means and has a laterally projecting tooth externally; means acting to retain the sleeve and connected circuit-closing means in their normal position; a pivotally supported latch arranged to swing toward and from the sleeve, which latch has a notch arranged to coöperate with the aforesaid tooth in locking the sleeve in an operative position of the circuit-closing means; means acting to swing the said latch toward the sleeve; a plunger extending into the sleeve and provided with means arranged to render the latch inoperative during the movement of the plunger into its normal position and to retain the latch in an inoperative position in the normal position of the plunger, and means acting to retain the plunger in its normal position.

30. In circuit-controlling means, the combination, with separated contacts adapted to participate in the formation of an electric circuit; circuit-closing means adapted to establish electrical connection between the contacts and normally in an inoperative position, and a movable block bearing the circuit-closing means, of a sleeve operatively connected with the block to actuate the circuit-closing means into an operative position and having a laterally projecting tooth externally; a suitably supported latch arranged to move toward and from the sleeve, which latch has a toothed portion arranged to coöperate with the aforesaid tooth in locking the sleeve in an operative position of the circuit-closing means; means acting to move the latch toward the sleeve, and a plunger extending into the sleeve and operatively connected with the sleeve to actuate the latter to render the circuit-closing means operative and provided with means arranged to render the latch inoperative during the movement of the plunger into its normal position and to retain the latch in an inoperative position in the normal position of the plunger.

31. In circuit-closing mechanism, the combination, of a casing forming a chamber; two laterally spaced contacts arranged within the upper portion and supported but insulated from the casing and adapted to participate in the formation of an electric circuit; two laterally spaced contacts arranged within the lower portion of the aforesaid chamber and insulated from the casing and adapted to participate in the formation of the said electric circuit; a vertically movable insulating block arranged and movable within the chamber between the upper and lower con-

tacts; circuit-closing means borne by the said block and comprising two contact-fingers adapted to electrically connect the different upper contacts respectively with the different lower contacts respectively during the downward movement of the block; block-lowering means, and means for actuating the block from its lower into its upper position.

32. In circuit-controlling mechanism, the combination, of a casing forming a chamber; two suitably supported laterally spaced contacts arranged within the upper portion of the chamber and insulated from the casing and adapted to participate in the formation of an electric circuit; two laterally spaced contacts arranged within the lower portion of the chamber and insulated from the casing and adapted to participate in the formation

of the said electric circuit, and circuit-closing means comprising two suitably supported 20 movable contact-fingers insulated from each other and adapted to electrically connect the different upper contacts respectively with the different lower contacts respectively during the downward movement of the said contact-fingers; means for actuating the said contact-fingers simultaneously to close the circuit, and means acting to retain the said contact-fingers in their normal position.

In testimony whereof, I sign the foregoing 30 specification, in the presence of two witnesses.

WILLIAM J. BARR.
